UNITED STATES PATENT OFFICE.

CHARLIE M. NICHOLS AND CHARLES M. BURNETT, OF BEAUMONT, TEXAS.

TRACE-FASTENER.

SPECIFICATION forming part of Letters Patent No. 671,292, dated April 2, 1901.

Application filed August 21, 1900. Serial No. 27,587. (No model.)

To all whom it may concern:

Be it known that we, CHARLIE M. NICHOLS and CHARLES M. BURNETT, citizens of the United States, residing at Beaumont, in the 5 county of Jefferson and State of Texas, have invented new and useful Improvements in Trace-Fasteners, of which the following is a specification.

Our invention relates to trace-fasteners; 10 and the objects of the same are to provide a simple, efficient, and reliable fastener which will when in use, at all times and under all circumstances, hold the trace in connection with the end of the whiffletree and which will 15 prevent undue wear on the cockeye or hole in the end of the trace. We attain these objects by means of the construction shown in the accompanying drawings, which form a part of this specification, and in which— 20 Figure 1 is a perspective view of the end of a whiffletree and the trace secured thereto by a fastener made in accordance with our invention. Fig. 2 is a detail plan view of our spring-fastener applied to a whiffletree having 25 an ordinary cockeye-fastener thereon. Fig. 3 is a side view of the end of the whiffletree shown in Fig. 1 with the trace removed.

In said drawings the numeral 1 designates a whiffletree of ordinary construction having 30 a rounded outer end 2 and tapering flattened sides 3. A notch 4 may be formed in the rear edge of the whiffletree. Secured to the front edge of the whiffletree is my spring trace-fastener, which consists of a single piece of 35 spring-wire of the proper gage bent to form a fastening-loop 5, a spiral coil 6, and a terminal end 7, extending outward in the same plane as the whiffletree. The fastening-loop 5 is provided with two openings 8 for the 40 attaching-screws 9, said openings being formed by bending the wire-strands outward, while the strands between the openings are brought together at 10 to lie in contact or substantially so. One terminal end of the 45 wire is then bent around the other strand, as at 11, and from thence said strand is continued to form a spiral coil 6 to give greater resiliency to the spring, and from the coil the strand is bent into a curved arm 13 and thence 50 continued to near the end, where it is bent at right angles to form the retaining-finger 7. The curved arm 13 normally lies at a distance

from the whiffletree, and the finger 7 is located substantially in line with the outer wall of the notch 4 in the rear edge of the whiffle- 55 tree.

To connect the trace to the whiffletree, the eye 14 therein is engaged at its front portion 15 with the retaining-finger 7, and the rear end of the eye is then pushed over the round- 60 ed end of the whiffletree. To detach the trace, the spring-arm 13 may be compressed and the trace pulled around the outer end of the whiffletree and then detached from the finger 7.

It will be noted that when the trace is connected to the whiffletree end the spring-arm 13 pushes the trace toward the front and holds the eye 14 steadily in engagement with the rear edge of the whiffletree, and thus preventing the eye from shifting about and wearing 70 the eye and the end of the whiffletree. It will also be apparent that our device is simple and efficient for its purpose and that it would be practically impossible to detach the trace from the whiffletree accidentally while 75 in use, as the spring is located at a point not liable to be compressed by accidental means and the trace-eye at the same moment be pushed in a curved line outward off the whiffletree. 80

An ordinary cockeye, as shown in Fig. 2, may be secured to the end of a whiffletree by our fastener in a manner to be secured and which will not rattle.

Having thus fully described our invention, 85 what we claim is—

A trace-fastener consisting of a single piece of spring-wire bent to form a fastening-loop, a plurality of openings in said loop for fasteners to secure the device to the front edge 90 of a whiffletree, a spiral coil formed in said wire, a curved arm extending outward from the coil at an angle to the whiffletree, and the terminal end of said curved arm being formed into a retaining-finger for the trace- 95 eye, substantially as described.

In testimony whereof we have hereunto set our hands in presence of two subscribing witnesses.

CHARLIE M. NICHOLS.
CHARLES M. BURNETT.
